INVENTOR:-
LEONARD BOX.

BY
W. L. Dempsey.
ATTORNEY.

UNITED STATES PATENT OFFICE.

LEONARD BOX, OF EAST ST. LOUIS, ILLINOIS.

FURNACE.

Application filed January 8, 1927. Serial No. 159,877.

My invention relates to furnaces, and especially to furnaces adapted to burn bituminous coal.

The chief object of my invention is to provide means for superheating all the air entering into the process of combustion.

Another object of my invention is to provide means for directing superheated air into the combustion chamber at various points and 10 in varying volume at different points.

The present application is intended to be supplementary to an application filed by me on the 2nd day of September, 1926, bearing Ser. No. 133143.

15 In the drawings:

Fig. 1 is a vertical cross section of my improved furnace.

Fig. 2 is a horizontal section along the line 2—2 in Fig. 1.

20 It has long been known that the processes of combustion are materially improved when the air is superheated and, also, when the air can be directed into the combustion chamber in such a manner as to create a degree of turbulence thereby more thoroughly mixing the gases of combustion and atmospheric air.

It is, also, well known that combustion is more complete when the air can be admitted in such quantities and in such a manner as to 30 furnish sufficient air for complete combustion at every point within the combustion chamber.

In order to bring about the results above noted, I have designed a furnace in which all 35 of the air admitted to the combustion chamber is pre-heated after the fire is kindled and is, also, directed into the combustion chamber in a divided stream, the major portion flowing in over the top of the fuel, and the minor 40 portion being directed to a combustion chamber in which only gas and air is admitted.

A hollow base 1 encloses the ash pit 2, which may be hermetically sealed by the door 3. Grate bars 4 are superimposed on the base 1. 45 An annular gas chamber 5 is superimposed on the base 1, separated from the fuel being consumed by the walls of the fire bowl 6, the lower marginal edge of which is provided with a plurality of suitable openings 7 to permit gases to escape from the fire bowl 6 into the gas combustion chamber 5, as indicated by the arrows 8.

Concentric with the fire bowl 6 an annular air chamber 9 is provided and so positioned 55 between the fire bowl 6 and the gas combustion chamber 5 that the air entering therein

is highly superheated, and due to the resulting expansion of the air it flows with increased velocity in the direction of the arrows designated as 8. Above the top of the fire bowl 6, which is outwardly flanged, as indicated at 10, a downwardly and inwardly turned flange or lip 11 is provided to direct the air from the annular air chamber 9 downwardly and inwardly into the fire, thus the draft is sufficient 60 to cause the flow of air and gases through the openings 7 into the gas combustion chamber 5, from whence they escape through the flue 12, as indicated by the arrows 13.

It is apparent that combustion would be incomplete for want of sufficient air and much fuel would be wasted up the stack in the form of carbon monoxide if no provision was made to admit supplementary air into the gas combustion chamber 5. Therefore, a plurality of holes or air ports 14 are provided in the bottom of the air chamber 9, which are best shown in Fig. 2.

The air thus introduced into the gas combustion chamber 5 is regulated by the size of the holes 14, thus I have brought about a two-stage combustion in which the fuel is first coked and the gases generated therefrom turned into a gas combustion chamber.

Under certain conditions I have found it necessary to admit a quantity of air to the base of the fire, and for this purpose I have provided a supplementary conduit 15, which directs air to the base of the fire, as indicated by the arrow 16.

A damper 17 is provided which is used only in starting the fire when the door of the ash pit 3 is open or air admitted at that point and the draft for kindling is direct, the damper 17 being open. By thus dividing and superheating all the air entering into the process of combustion, I have provided a furnace that readily shows a combustion efficiency of 95%.

Having fully described my invention and its method of construction and operation, what I claim as new and useful and desire to protect by Letters Patent is:—

1. A furnace, comprising an inner combustion chamber surrounded by an outer combustion chamber in inter-communication, said outer combustion chamber being concentrically disposed about the base of the said inner combustion chamber and in open communication with a smoke flue, an annular air chamber concentrically disposed about the upper portion of said inner combustion chamber in open communication therewith, the

lower portion of said air chamber being in regulated and restricted communication with said outer combustion chamber.

2. A furnace, comprising a combustion chamber surrounded by means for preheating all the air admitted to the said combustion chamber after the fire has once been kindled, means for directing preheated air into the said combustion chamber from all points around the upper edge thereof, means for directing said preheated air inwardly and downwardly into said combustion chamber, a gas combustion chamber adjacent to and surrounding said combustion chamber, means for admitting gas and air into said gas combustion chamber and means for permitting the escape of the products of combustion.

3. A furnace of the class described, comprising a fire bowl ported about its lower periphery, a gas combustion chamber con-

centrically disposed about the base of said fire bowl and in open communication therewith by means of said ports, an air chamber concentrically disposed about the upper portion of said fire bowl and extending downwardly between said fire bowl and said gas combustion chamber, means for admitting atmospheric air into said air chamber, means for directing a portion of said admitted air over the top of said fire bowl into said fire bowl, means for admitting a portion of said atmospheric air into said gas combustion chamber thereby causing combustion to take place in two stages, the first stage taking place in the fire bowl and the second stage taking place in the gas combustion chamber.

In witness whereof I have hereunto affixed my signature this 16th day of December, 1926.

LEONARD BOX.
